PICKER CHECK FOR LOOMS

Carl D. Brown, Hopedale, Mass., assignor to
Draper Corporation, Hopedale, Mass., a cor-
poration of Maine

Application November 30, 1942, Serial No. 467,330

9 Claims. (Cl. 139—165)

The present invention relates generally to picking mechanisms for fly shuttle looms and, as illustrated herein, relates more particularly to picker stick checking mechanism.

In high speed looms, the picker stick moves very rapidly during its picking movement and hence appreciable force is required to check the picker stick at the end of such movement. The return movement of the picker stick is not so rapid but this return movement must also be checked to impart a checking action to the shuttle as the latter returns to its initial position. Various picker stick checking devices have been proposed and the type which is most generally satisfactory includes an endless strap embracing the picker stick and which is moved bodily by engagement with the picker stick when the latter approaches either end of its stroke. Friction devices are applied on each side of the path of movement of the picker stick and engage the check strap. These friction devices are adjustable independently of each other and hence it is practically impossible to so adjust the devices that equal friction is applied to each run of the check strap. This is objectionable since the strap will slide more freely in one friction device than in the other which results not only in excessive wear on the strap but also causes undesirable deflection and twisting of the picker stick.

One object of the present invention is to provide picker stick checking mechanism whereby the above mentioned difficulties will be overcome. To this end, the picker stick check is provided with means for applying equal friction to the check strap on each side of the path of movement of the picker which includes means arranged for frictional engagement with the front and back runs of the check strap and a connecting member arranged to apply pressure to said friction means equally on the front and back runs of the check strap.

With the above and other objects and features in view, the invention will now be described with particular reference to the accompanying drawing which illustrates a preferred embodiment of the invention and in which:

Fig. 1 is a view in front elevation of the left hand end portion of a loom embodying the present invention;

Fig. 2 is a view partly in section taken along the line II—II of Fig. 4;

Fig. 3 is a view in cross section taken along the line III—III of Fig. 1; and

Fig. 4 is a view in cross section taken along the line IV—IV of Fig. 1.

The loom to which the present invention is applied is of usual construction and there is shown in the drawing only that portion of a loom which is necessary to the understanding of the present invention.

Fig. 1 of the drawing shows a portion of the left hand end of a usual lay beam 10 which is arranged for reciprocation forwardly and rearwardly of the loom during operation thereof. The loom is also provided with the usual picker stick 12 which is moved inwardly and outwardly longitudinally of the lay by the usual picking mechanism. The usual metal lay end 14 is secured to the end of the lay by suitable fastenings.

15 The check strap 16, preferably formed of leather, shown in the drawing is bent to form a flattened loop and the overlapping ends are secured together by suitable bolts and nuts. An endless check strap could, of course, be used if so desired but it is preferred, however, to use the type shown since it is less expensive than the endless type. The check strap 16 is supported directly beneath the lay beam 10 between suitable friction members which include front and 20 rear supporting members 18, 20 and which are fixed to the lay beam by bolts 22, 24 respectively. Each of these supporting members is substantially identical and, hence, it will be necessary to describe only one in detail.

25 The supporting member 18 is formed in one piece and, as best shown in Fig. 4, comprises a substantially vertical portion 26 and a substantially horizontal portion 28 which engage the front and bottom, respectively, of the lay beam 10. The horizontal portion 28 is provided with slots 30 which receive the bolts 22. The horizontal portion 28 is provided with a depending projection 32 constituting a friction member and having a forwardly extending shoulder 34 for limiting downward movement of the check strap 16. The outward face of the projection 32 is substantially flat and smooth so that the check strap 16 may be moved relatively thereto and in contact therewith without excessive wear on the strap. The member 18 is also provided with an outwardly extending rigid arm 36 which terminates short of the outer end of the metal lay end 14. The outer end portion of the arm 36 is provided with a hole in which the upper end of a substantially vertical pivot pin 38 is secured.

30 The pin 38 forms a pivot for the tensioning means which comprises a plate 40 having an inner end portion 42 which is substantially flat and which is located opposite to the downward projection 32. The outer end portion of the

plate 40 is slightly offset forwardly of the inner end portion 42 and is secured to a pivoted bracket 44 by suitable fastenings such, for example, as rivets 46. The bracket 44 is provided with a substantially vertical drilled hole into which the pin 38 of the arm 36 loosely fits. The bracket 44 is maintained in position on the pin 38 by a cotter pin 48. A washer 50 is interposed between the bottom of the bracket 44 and the cotter pin 48 to prevent binding between the cotter pin and the bracket. 10

The bracket 44 is provided with an outwardly extending arm 52 which extends slightly outwardly of the outer end of the metal lay end 14 and is provided with a tapered hole 54, the purpose of which will later become apparent. The bracket 44 is also provided with an outwardly extending arm 56, the outer end portion of which is provided with a forwardly extending lug or projection 58 located rearwardly of and in line with the tapered hole 54. 20

The tension member or plate 40 above described, and a similar member at the opposite side of the path of the picker stick, are normally urged toward each other and their associated depending projections or friction members 32 by a compression spring 60 having one end surrounding the lug 58 and seated against the adjacent surface of the rear bracket arm 56. The other or forward end of the compression spring 60 is seated against a shoulder 62 formed on a threaded bushing 64 which receives a screw 66 having a tapered head 68 which fits into the tapered hole 54 in the front bracket arm 52. The forward end of the tapered head 68 is provided with a screw driver slot 70. Thus when it is desired to adjust the tension of the plates 40 against the check strap, the screw 66 is turned to increase or decrease the tension of the spring 60. Since the head 68 of the screw 66 is tapered, the pressure of the spring thereon will permit the tapered head to be firmly seated in the tapered hole 54 and will prevent turning of the screw. 30

Since only one spring is used and since only one adjustment is necessary to vary the tension produced on the plates 40, it is apparent that the friction produced between the plates 40 and the depending projections 32 on the check strap 16 is equalized. Thus, the front and rear runs of the check strap 16 are equally free to move when engaged by the picker stick 12. Thus, the picker stick is checked by the check strap 16 without subjecting the picker stick to any torsional strains. 40

Having thus described my invention what I claim as new and desire to secure by Letters Patent of the United States is:

1. A picker check for looms having in combination a picker and a picker stick, a strap embracing the picker stick and arranged to be bodily moved by engagement with the picker stick when the latter approaches either end of its stroke, members arranged for engagement with the front and back runs of the strap, means for pressing the strap into engagement with each of said members, and a single member for varying the pressure of said pressing means. 50

2. A picker check for looms having in combination a picker and a picker stick, a strap embracing the picker stick and arranged to be bodily moved by engagement with the picker stick when the latter approaches either end of its stroke, supporting members arranged to engage the strap at each side of the path of movement of the picker stick, pivoted members arranged to press 70

the strap against each of said supporting members, and a resilient adjustable connection between said pivoted members for adjusting the pressure of each of said pivoted members equally against the strap. 5

3. A picker check for looms having in combination a picker and a picker stick, a strap embracing the picker stick and arranged to be bodily moved by engagement with the picker stick when the latter approaches either end of its stroke, stationary means arranged to engage the strap at each side of the path of movement of the picker stick, plates pivoted to each of said stationary means and arranged to press the strap against each of the stationary means, a spring tension device connecting said plates, and a member for adjusting the tension of said spring tension device to apply equal pressure to each of said pivoted plates. 15

4. A picker check for looms having in combination a picker and a picker stick, a strap embracing the picker stick and managed to be moved bodily by engagement with the picker stick when the latter approaches either end of its stroke, supporting members arranged to engage the strap at each side of the path of movement of the picker stick, plates pivoted to each of said members and arranged to press the strap against each of the members, said plates each having an outwardly extending portion, a compression spring interposed between said portions, and a member for varying the tension of said spring whereby equal pressure is applied to the strap at both sides of the path of movement of the picker stick. 25

5. A picker check for looms having in combination a picker and picker stick, a check strap embracing the picker stick and arranged to be moved bodily by engagement with the picker stick when the latter approaches either end of its stroke, supporting members for said check strap at each side of the path of movement of said picker stick, pivoted plates each having a surface arranged to press said check strap against said members, means for pivoting each of said plates to each of said members, resilient means connecting said plates and urging said plates against said check strap, and means for varying the pressure of said plates against said strap. 40

6. A picker check for looms having in combination a picker and picker stick, a check strap embracing the picker stick and arranged to be moved bodily by engagement with the picker stick when the latter approaches either end of its stroke, supporting members for said check strap at each side of the path of movement of said picker stick, said members each having a bearing surface engaged by said strap, plates pivoted to each of said members and each having a bearing surface engaging the check strap and pressing the latter against the bearing surface of the associated supporting member, an extension on each of said plates, spring means interposed between said extensions and pressing said plates against said strap, and means for adjusting the tension of said spring means to apply equal pressure to said strap through said plates. 50

7. A picker check for looms having in combination a picker and picker stick, a check strap embracing the picker stick and arranged to be moved bodily by engagement with the picker stick when the latter approaches either end of its stroke, supporting members for said check strap at each side of the path of movement of said picker stick, said members each having a bearing surface en- 70

gaged by said strap, plates pivoted to each of said members and each having a bearing surface for pressing the check strap against the bearing surface of the associated member, an extension on each of said plates projecting outwardly beyond the path of movement of the picker stick, a compression spring located between said extensions for applying equal pressure to each of said plates, and an adjusting member located between one of said extensions and one end of said spring for varying the tension of said spring.

8. In a loom, a lay, a picker and a picker stick, a strap embracing the picker stick and arranged to be moved bodily by engagement with the picker stick when the latter approaches either end of its stroke, supporting members fixed to the lay at each side of the path of movement of the picker stick, and presser members pivoted to each of said supporting members and pressing said strap against each of said supporting members, and means connecting said presser members for applying equal pressure thereto to insure equal movements of each run of said strap when engaged and moved by said picker stick.

9. In a loom, a lay, a picker and a picker stick, a strap embracing the picker stick and arranged to be moved bodily by engagement with the picker stick when the latter approaches either end of its stroke, supporting members fixed to the lay at each side of the path of movement of the picker stick, said members each having a bearing surface engaged by said strap, plates pivoted to each of said members and each having a bearing surface for pressing the strap against the bearing surface of the associated member, an extension on each of said plates projecting toward the outer end of the lay and beyond the path of movement of the picker stick, a compression spring interposed between said extensions and having one end thereof engaging one of said extensions, and means on the other of said extensions and engaging the other end of said spring for adjusting to tension of said spring to apply equal pressure to each of said plates whereby each run of said strap will move equally when engaged by and moved by said picker stick.
